[57] CLAIM

The ornamental design for a fused electrical plug, as shown and described.

DESCRIPTION

FIG. 1 is a perspective view of a fused electrical plug showing our new design;

FIG. 2 is a front view thereof;

FIG. 3 is a top view thereof, the bottom view being a mirror image with the exception of the placement of the prongs;

FIG. 4 is a rear view thereof;

FIG. 5 is an end view thereof; and,

FIG. 6 is an opposing end view thereof.

The broken lines are shown for illustrative purposes only and form no part of the claimed design.
